DESIGN FOR A GOLF BALL OR THE LIKE

Frank H. Cavignac, New York, N. Y.

Application November 17, 1936, Serial No. 65,986

Term of patent 3½ years

To all whom it may concern:

Be it known that I, Frank H. Cavignac, a citizen of the United States of America, and resident of New York City, county of Queens, and State of New York, have invented a new, original, and ornamental Design for Golf Balls or the Like, of which the following is a specification, reference being had to the accompanying drawing, forming part thereof:

In the drawing:

Figure 1 is an elevational view of a golf ball embodying the invention.

Figure 2 is an elevational view of the golf ball shown in Figure 1 after the same has been rotated through approximately 45° in a horizontal plane and in a vertical plane.

Figure 3 is a fragmentary sectional view taken along the line 3—3 of Fig. 2.

I claim:

The ornamental design for a golf ball or the like as shown.

FRANK H. CAVIGNAC,
